A. PETZOLD.

RUG.

No 16,751.

Patented June 22, 1886.

UNITED STATES PATENT OFFICE.

ADOLPH PETZOLD, OF PHILADELPHIA, PENNSYLVANIA, ASSIGNOR TO JOHN BROMLEY & SONS, OF SAME PLACE.

DESIGN FOR A RUG.

SPECIFICATION forming part of Design No. 16,751, dated June 22, 1886.

Application filed May 10, 1886. Serial No. 201,748. Term of patent 3½ years.

To all whom it may concern:

Be it known that I, ADOLPH PETZOLD, a citizen of the United States, and a resident of Philadelphia, Pennsylvania, have invented and produced a new and original Design for Rugs, of which the following is a specification, reference being had to the accompanying photographic illustration, to which reference is made.

10 In the illustration, A is a central rectangular panel. B B are scroll-leaves; C C, fanciful flowers; D, a cluster of dotted figures in the general form of flowers; E E, large fanciful figures in the general form of grape-leaves; F F, triple-leaved horned fanciful figures; G, an ornamental border provided with scalloped figures H H, the apex of each scallop terminating in multiple points I I.

15 J J are flowers, and K K fanciful designs, 20 these flowers and the latter-named designs filling in the borders.

The leading features of my design will be fully set forth in the following claims.

What I claim as new is—

1. In a design for rugs, the central rectangular panel, A, with scroll-leaves B B, fanciful flowers C C, bunches or clusters of dotted figures D, large leaves E E in the general form of grape-leaves, triple-leaved horned fanciful figures F F, and ornamental border G, substantially as described and shown. 25

2. In a design for rugs, the ornamental border G, provided with scalloped figures H H, the apex of each scallop terminating in multiple points I I, with flowers J J, and fanciful 30 designs K K, substantially as described and shown. 35

ADOLPH PETZOLD.
